UNITED STATES PATENT OFFICE.

CHARLES F. MONROE, OF MERIDEN, CONNECTICUT.

DESIGN FOR A SALT-CELLAR, &c.

SPECIFICATION forming part of Design No. 20,788, dated June 2, 1891.

Application filed May 5, 1891. Serial No. 391,678. Term of patent 7 years.

To all whom it may concern:

Be it known that I, CHARLES F. MONROE, of Meriden, in the county of New Haven and State of Connecticut, have invented and produced a new and original Design for Salt-Cellars or Pepper-Boxes; and I do hereby declare the following to be a full, clear, and exact description of said invention, reference being had to the accompanying drawing, and to the letters of reference marked thereon, which form a part of this specification.

The said photograph represents one of my salt-cellars as tilted somewhat upon its side to clearly show the leading feature of my design, which consists in the top or upper surface having a scalloped edge with grooves or lines converging toward the center.

A is the upper surface of the salt-cellar, and a are lines radiating from the raised center, which supports the perforated sprinkler. The outer edge of the surface is curved between the lines, as at b and b', and preferably the said curves are alternately different distances from the center, the whole forming an irregu-

lar scalloped edge, and with the lines a having the appearance somewhat of a daisy or chrysanthemum, some of the petals of which are shorter than the others.

To enhance the beauty of the design, I may have the portion of the body of the salt-cellar that is just below the outer ends of the shorter petals formed with projecting curves, as at c.

This design is for the shape of the upper surface of the body of the salt-cellar and is irrespective of the shape of the lower part and of any painting or other surface ornamentation.

As is obvious, the same design may serve for pepper-boxes.

What I claim is—

The design for a salt or pepper box, substantially as shown and described.

In testimony whereof I affix my signature in presence of two subscribing witnesses.

CHARLES F. MONROE.
